SAFETY CAP FOR KNITTING NEEDLE-POINT

William H. Porter, Northport, N. Y., and Clarence M. Porter, Lakeside, Point Claire, Quebec, Canada

Application April 15, 1940, Serial No. 329,677

7 Claims. (Cl. 66—117)

This invention relates to new and useful improvements in a safety cap for a knitting needle-point.

The invention has for an object the use in combination with a knitting needle of a flange mounted on the knitting needle spaced slightly from its blunt end, and a member mounted on the blunt end and engageable on the pointed end for preventing loops from dropping off the needle.

Still further the invention proposes to characterize said member by the fact that it is annular in formation, and of friction material capable of frictionally maintaining its position on the needle.

Still further the invention proposes a novel arrangement for increasing the frictional resistance between the member and the needle.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a knitting needle with a safety cap constructed in accordance with this invention and associated therewith.

Fig. 2 is a fragmentary enlarged detailed view of a portion of Fig. 1 showing the member on the pointed end of the needle and showing certain parts in section.

Fig. 3 is a fragmentary enlarged sectional view illustrating a portion of Fig. 2.

Fig. 4 is a transverse vertical sectional view taken on the line 4—4 of Fig. 3.

Fig. 5 is another sectional view similar to a portion of Fig. 2 but illustrated on an enlarged scale and disclosing another embodiment of this invention.

Fig. 6 is a sectional view taken on the line 6—6 of Fig. 5.

The safety clip for knitting needles, according to this invention, is used in combination with a knitting needle 10. This knitting needle has a pointed end 10^a and a blunt end 10^b. A flange 11 is permanently mounted on the knitting needle and spaced inwards slightly from its blunt end. This flange may be fused or secured to the material of the needle in any convenient manner. A member 12 is normally mounted on the blunt end of the needle, as illustrated in Fig. 1, and is removable and engageable on the pointed end 10^a of the needle as illustrated in Fig. 2 for preventing knitting loops from dropping off the needle.

This member 12 comprises an annular rubber member. Frictional resistance is depended upon to maintain the member 12 in its various positions on the knitting needle.

The annular member 12 is provided with a rigid ring 13 of composition material or other rigid material embedded within a peripheral groove 14 formed in the annular member 12 for holding the outer area of the member from expanding. Consequently, when the member 12, which is made of rubber, is forced upon the knitting needle the portions between the knitting needle and the ring 13 will be compressed. This compression is depended upon to frictionally maintain the position of the member on the knitting needle.

In Figs. 5 and 6 another embodiment of the invention is disclosed which is somewhat similar to the form shown in Figs. 3 and 4, distinguishing merely in the fact that the rubber member 12' is provided with a pair of interengaged rigid annular or ring elements 13' and 13'' arranged in a manner so that the material of the rubber member 12 adjacent the knitting needle 10 may be more securely clamped. Specifically, the annular member 13' is the outer one of the two and is formed with a slot 15 through which a pin 16 extends. This pin is permanently mounted on the inner annular member 13''. The adjacent faces of the inner and outer annular members 13' and 13'' are elliptical, as illustrated in Fig. 8, the major axis being on the vertical, and the minor axis being on the horizontal. The inner annular member 13'' is formed with a split 18 in the vertical direction, directly opposite the pin 16.

With the parts as illustrated in Figs. 5 and 6 the member 12' may be slipped upon the knitting needle. If it is desired to securely mount this member on the needle the pin 16 is moved to the other end of the slot 15. This rotates the inner annular member 13'' relative to the outer member 13'. Thus the major axes of the elliptical surfaces of these annular members are moved out of alignment with each other, and the side portions of the annular member 13'' will be forced together, compressing the material of the rubber member 12' and so adding to the frictional resistance of the member 12' on the needle 10.

It is to be understood that the member 12 may be of rubber or of any suitable material such as felt, cork, etc.

While we have illustrated and described the preferred embodiments of our invention, it is to be understood that we do not limit ourselves to the precise constructions herein disclosed and the right is reserved to all changes and modifications.

coming within the scope of the invention as defined in the appended claims.

Having thus described our invention, what we claim as new, and desire to secure by United States Letters Patent is:

5. In combination with a knitting needle, a flange mounted on said knitting needle spaced slightly from its blunt end, and a member mounted on said blunt end and removable and engageable on the pointed end for preventing loops from dropping off the needle when not used, said member comprising an annular ring of rubber, an annular ring of rigid material embedded therein.
10. 2. In combination with a knitting needle, a flange mounted on said knitting needle spaced slightly from its blunt end, and a member mounted on said blunt end and removable and engageable on the pointed end for preventing loops from dropping off the needle when not used, said member comprising an annular ring of rubber, an annular ring of rigid material embedded therein, specifically within a groove in the outer sides thereof.
15. 3. In combination with a knitting needle, a flange mounted on said knitting needle spaced slightly from its blunt end, and a member mounted on said blunt end and removable and engageable on the pointed end for preventing loops from dropping off the needle when not used, said member comprising an annular member of rubber having a groove formed in its periphery, a pair of interengaged rings of rigid material mounted in said groove, the inner ring being split, the contacting faces of said ring being slightly elliptical, and means for turning said rings slightly relative to each other.
20. 4. In combination with a knitting needle, a flange mounted on said knitting needle spaced slightly from its blunt end, and a member mounted on said blunt end and removable and engageable on the pointed end for preventing loops from dropping off the needle when not used, said member comprising an annular member of rubber having a groove formed in its periphery, a pair of interengaged rings of rigid material mounted in said groove, the inner ring being split, the contacting faces of said ring being slightly elliptical, and means for turning said rings slightly relative to each other, comprising a pin pro-

jecting from the inner ring and engaging through a slot formed in the outer ring.

5. In combination with a knitting needle, a member engageable upon the pointed end of said needle for preventing loops from dropping off 5 said needle when not in use, comprising an annular rubber member slidably engageable on said needle and formed with a groove in its periphery, a pair of interengaged metal rings mounted in said groove and having their engaging faces elliptical, and means whereby said inner ring may be moved relative to said outer ring to compress said rubber member to increase the frictional engagement of said member on said knitting needle.

10. 6. In combination with a knitting needle, a member engageable upon the pointed end of said needle for preventing loops from dropping off 10 said needle when not in use, comprising an annular rubber member slidably engageable on said needle and formed with a groove in its periphery, a pair of interengaged metal rings mounted in said groove and having their engaging faces elliptical, and means whereby said inner ring may be moved relative to said outer ring to compress 15 said rubber member to increase the frictional engagement of said member on said knitting needle, comprising a pin mounted on the outer periphery of said inner ring and projected through a slot formed in said outer ring to be 20 manually gripped for turning the inner ring.

25. 7. In combination with a knitting needle, a member engageable upon the pointed end of said needle for preventing loops from dropping off 25 said needle when not in use, comprising an annular rubber member slidably engageable on said needle and formed with a groove in its periphery, a pair of interengaged metal rings mounted in said groove and having their engaging faces elliptical, and means whereby said inner ring 30 may be moved relative to said outer ring to compress 30 said rubber member to increase the frictional engagement of said member on said knitting needle, comprising a pin mounted on the outer periphery of said inner ring and projected through a slot formed in said outer ring to be 35 manually gripped for turning the inner ring.

35. 8. In combination with a knitting needle, a member engageable upon the pointed end of said needle for preventing loops from dropping off 35 said needle when not in use, comprising an annular rubber member slidably engageable on said needle and formed with a groove in its periphery, a pair of interengaged metal rings mounted in said groove and having their engaging faces elliptical, and means whereby said inner ring 40 may be moved relative to said outer ring to compress 40 said rubber member to increase the frictional engagement of said member on said knitting needle, comprising a pin mounted on the outer periphery of said inner ring and projected through a slot formed in said outer ring to be 45 manually gripped for turning the inner ring.
